UNITED STATES PATENT OFFICE.

CLARENCE H. RASMUSSEN, OF VALLEY JUNCTION, IOWA.

KNOCKDOWN STRUCTURE.

Application filed August 22, 1921. Serial No. 494,232.

To all whom it may concern:

Be it known that I, CLARENCE H. RASMUSSEN, a citizen of the United States, and a resident of Valley Junction, in the county 5 of Polk and State of Iowa, have invented a certain new and useful Knockdown Structure, of which the following is a specification.

The object of my invention is to provide a 10 knock-down structure, such for instance as for pop corn stands, which is of simple, durable and inexpensive construction.

A further object is to provide such a top, which can be readily and easily put together 15 or taken apart, so that it may be transported or stored in a relative small space.

A further object is to provide in such a top, certain features of construction, whereby the top may be made strong and rigid 20 and properly supported.

With these and other objects in view, my invention consists in the construction, arrangement and combination of the various parts of my device, whereby the objects contemplated are attained, as hereinafter more 25 fully set forth, pointed out in my claims, and illustrated in the accompanying drawings, in which:

Figure 1 shows a front elevation of a 30 knock-down top embodying my invention as applied to a frame, such as that of a pop corn stand.

Figure 2 shows a detailed, sectional view taken on the line 2—2 of Figure 1.

Figure 3 shows an end elevation of the 35 top.

Figure 4 shows a detailed, sectional view taken on the line 4—4 of Figure 3.

Figure 5 shows a detailed, sectional view 40 taken on the line 5—5 of Figure 4.

Figure 6 shows a detailed, sectional view taken on the line 6—6 of Figure 3; and

Figure 7 shows a detailed, sectional view 45 taken on the line 7—7 of Figure 6.

Figure 8 is a detail of a corner construction.

In the accompanying drawings, I have used the reference numeral 10 to indicate generally the frame of a pop corn stand or 50 the like, comprising upright members in the form of a rectangular frame, having at their upper ends on their insides angle irons 11 and on their outer surfaces at their upper edges brace strips 12, shown in detail in

55 Figure 2.

The angle irons 11 are arranged with an

upright flange adjacent to the wall frame 10 and with an upper horizontal, inwardly, extending flange, as shown in Figure 2.

The knock-down top hereinafter more 60 fully described is designed to rest upon the upper edge of the frame 10 and upon the horizontal flanges of the angle irons 11, so that the top may be readily and easily removed and need not be attached by means 65 of bolt screws or the like.

The knock-down top has a lower rectangular frame, comprising a horizontal strip 13 forming each side of the frame and resting on the upper edge of the frame 10. The 70 strip 13, at each side and end of the lower frame of the top member, has at its inner edge a downwardly extending flange 14, which extends downwardly inside the horizontal flange of the adjacent angle iron 11, 75 as illustrated for instance in Figure 2, and holds the top from sliding movement in any direction.

At the outer edge of each strip portion 13 is a vertical upward extension 15. 80

At the ends and back of the top, there are formed upwardly opening channels, comprising channel members 16 bent downwardly from the upper edge of the members 15 and folded against the members 15, 85 as shown in Figure 5.

At the lower end of each portion 16 is a channel bottom 17 at the inner edge of which is an upwardly extending channel wall 18. The material is bent downwardly at the upper edge of the wall 18 forming an inner member 19 parallel with the wall 18 and serving to support and brace said wall. 90

At the front of the top are formed two channels like that just described. The front channel is the same as that already described, comprising the members 16, 17 and 18. The member 19 at the front of the top informs the outside wall of the second or inner channel, which has the bottom 20 and 100 the inner wall 21.

At the upper edge of the wall 21, the material is again bent downwardly as at 22, forming a portion, which projects downwardly below the channels and is designed 105 to substantially rest on the strip 13 for forming a proper support for the channels.

The channels hereinbefore described serve to receive the lower edges of panes of glass, which forms the side and end walls of the 110 removable knockdown top.

At each corner of my improved top is an

upright angle iron post 23. The edges of the flanges of the angle iron post 23 are in each case folded as at 24, (see Figure 4) to form channels.

5 A brace member is provided in connection with each post 23, comprising an angle iron member 25, shown for instance in section in Figure 4. Spaced inwardly from the post 23, as illustrated, and at the ends of its flanges 24, are extensions 26 and 27 respectively, which are inclined outwardly to the post member 23.

10 At the ends of the inclined portions 26 and 27 are portions 28 and 29, which are projected into and receive the channels formed between the flanges of the post 23 and the portions 24.

15 The ends of the members 18 and 19 terminate short of the corners of the knock down top, as shown for instance in Figure 4. The members 15 and 16 extend to the corners beyond the ends of the members 18 and 19.

20 The portions 26 and 27 and 28 and 29 are cut away at the lower ends of the corner posts and terminate short of the lower ends of the posts 23. The portions 24 of the post 23 are cut away at their lower ends and terminate at such points as to rest upon the members 15 and 16 (Fig. 5).

25 Arranged adjacent to the inner surface of the angle iron post members 25 are angle irons 30, the ends of which project beyond the members 26 and 27, as shown in Figure 4 and overlap the ends of the members 19 and 18.

30 It will, of course, be understood that at the front of the frame, the angle irons 30 overlap the members 21 and 22.

35 40 At each corner post near the lower portion thereof a screw bolt 31 is extended through one flange of the post 23 and through one flange of the post member 25 and the angle iron 30, as shown in Figure 4, and is provided with a nut 32 at its inner end for thereby holding the post members 23, 25 and 30 together.

45 50 The angle iron members 30 are provided at their upper ends with inwardly extending horizontal portions 33 forming supporting shelves, there being one such shelf at each corner.

55 60 At the upper part of the top, there is provided a rectangular frame comprising angle iron members, each having a horizontal flange 34 and an outer downwardly extending flange 35. The flanges 35 are cut away at proper places to permit the flanges 34 to rest on the shelf members 33, as indicated for instance in Figures 2, 6 and 7. The flanges 34 may be secured to the shelf members 33 by means of screw bolts 36, as shown in Figure 7 and at the ends of the flanges 34, there may be provided down-turned portions 38, as shown in Figure 7, received

between the members 30 and 25, at the upper ends of the latter.

65 Spaced just outwardly from the flange 35 at the back and ends of the knock-down top are guide strips 39, the ends of which are bent or folded over on the inner sides of the strips 39, as illustrated at 40 in Figure 8. The bent over portions 40 are so arranged that the strips 39 are thus spaced from the flanges 35 to permit a space into 75 which the panes of glass 41 may be inserted. The portions 40 may be soldered or otherwise secured to the upper frame member, having the flanges 34 and 35.

70 80 At the front of the top, there is formed at the lower part of the flange 35, the spaced, parallel downwardly, opening channels 43 and 44, similar to the channels hereinbefore described. At the inner side of the channel 44 is a brace member 45, extending 85 upwardly and abutting against the flange 34, all as illustrated in Figure 2.

85 90 It will thus be seen that there are provided near the lower part of the front of the knock-down top, two upwardly opening channels, and near the upper part of said top at the front thereof, two corresponding downwardly, opening channels. Mounted in these two pairs of channels are sliding panes of glass 46 and 47, each being a little 95 longer than half the length of the knock-down top.

95 100 These panes of glass 46 and 47 may be slid for opening the top to permit access to the interior thereof.

105 110 There is provided a cover for my knock-down top, comprising a top member 48, having the ornamental corner posts 49 and provided with the exterior annular downwardly extending flange 50.

115 120 The cover may have a central ornamental post or ventilator 51.

125 130 In the assembling of my knock-down cover, the frame, comprising the members 13 and 14, is assembled and fastened together, and the corner posts are then bolted to such frame. The glass members 46 and 47 are then placed in the lower receiving channel therefor and the upper frame, having the members 35 and 34, is then placed in position resting on the shelf members 33 and with the upper edges of the glass panes 46 and 47 received in the upper receiving channels therefor.

135 140 The bolts 36 are then placed in position. The glass panes 41 may then be slipped in from above between the flanges 35 and the members 39 until their lower edges are received between the members 16 and 18.

145 150 The cover member may then be placed in position and the device is completed.

155 160 It is to be noted that at the front of the device, there are two panes of glass, as shown in Figures 1 and 2, which are slidable in panels above and below to substantially over-

lap for their entire width to permit access to the inside of the top, and which may be readily slid to position, where they only slightly overlap, as in Figure 1.

5 At the back and sides of the device, respectively, I provide only one pane of glass. In each instance, the lower edge of the side or back pane is received in a suitable panel, while the upper edge is received between the 10 flange 35 and the spaced strip 39.

By following these operations in the inverse order the top may be taken apart and packed in small space for storage or transportation.

15 I claim as my invention:

1. In a device of the class described, the combination of a supporting frame with a removable top comprising corner posts, an upper frame connecting the upper ends of 20 said posts, a lower frame connecting the lower ends of said posts and formed with glass receiving channels, and a flat surfaced supporting member adapted to rest on the supporting frame, having at its inner edge 25 a downwardly projecting flange received within said supporting frame for positioning the top and preventing the horizontal movement thereof on the main frame, and glass panes supported between said upper and 30 lower frames for forming the sides of said removable top.

2. A knock-down top for pop corn stands and the like, comprising a lower rectangular frame having a horizontal portion provided 35 at its inner end with a downwardly projecting flange, upwardly opening channels on said lower frame, corner posts secured to said lower frame, each comprising an angle iron member, a second angle iron member 40 spaced inwardly from the first angle iron member and provided with portions connected with said first angle iron member, a third angle iron member secured to the second angle iron member and having its

flanges for portions of their length spaced 45 from the second angle iron member, shelf members formed at the upper ends of said corner posts and upper frames supported on said shelf members, comprising a horizontal portion and a downwardly extending flange 50 portion, guide devices on said upper frame, wall members received in said channels and said guide devices and a cover for said knock-down top having a peripheral downwardly extending flange. 55

3. In a device of the class described, the combination of a lower frame, with a top structure for coacting therewith having at its lower part, a frame provided with a flange adapted to rest on said first frame and a downwardly projecting portion to fit within and project below the top of said first frame, an upper frame, corner posts connecting the upper and lower frames, said frames and corner posts being formed with 60 pane holding elements, said pane holding elements including spaced guide and retaining members on the upper frame, through which panes may be inserted from above and a cover for said upper frame. 65

4. In a device of the class described, a supporting frame, a removable top therefor, having supporting corner posts and having frames connected with the posts at the top and bottom thereof, said top having means for receiving and supporting glass panes, part of said panes being movable to permit access to the interior of the top, the lower frame member of the top having a flat portion adapted to rest on said first frame, and a downwardly extending flange at the inner edge of said flat portion designed to project into said first frame and to stand close to said first frame for preventing horizontal movement of the top. 70

75 Des Moines, Iowa, February 5, 1921.

CLARENCE H. RASMUSSEN.
